[57] CLAIM

The ornamental design for a beverage cup, as shown and described.

DESCRIPTION

FIG. 1 is a front elevational view of a beverage cup showing my new design, a similar view taken from the rear thereof will be a mirror image;

FIG. 2 is a top plan view thereof; and

FIG. 3 is a right side elevational view thereof, a similar view taken from the opposite side except for the omission of the handle will be identical.

FIG.-1

FIG.-3
